UNITED STATES PATENT OFFICE.

EDWARD S. COBB, OF WHITTIER, CALIFORNIA, ASSIGNOR TO COBB SHOCKLESS CROSSING CORPORATION, OF NEW YORK, N. Y., A CORPORATION OF NEW YORK.

CROSSING-OPERATING SYSTEM.

1,257,279.

Specification of Letters Patent. Patented Feb. 19, 1918.

Application filed August 12, 1916. Serial No. 114,563.

To all whom it may concern:

Be it known that I, EDWARD S. COBB, a citizen of the United States, residing at Whittier, in the county of Los Angeles, 5 State of California, have invented new and useful Improvements in Crossing-Operating Systems, of which the following is a specification.

This invention relates to systems for operating railway crossings and the like; and it is the object of this invention to provide a simple and reliable system and mechanism for operating crossings and the like for passage of trains in different directions there- 10 over.

The nature of my invention and the details of a preferred and specific embodiment will be best understood from the following detailed description of a preferred form of 15 system and mechanism embodying my invention, reference being had to the accompanying drawings in which:

Figure 1 is a plan, with parts broken away, showing a form of crossing to be operated by my system. Fig. 2 is a detail section taken as indicated by line 2-2 on Fig. 1; Fig. 3 is a section taken as indicated by line 3-3 on Fig. 1; Fig. 4 is a section taken as indicated by line 4-4 on Fig. 2; Fig. 5 is a diagram illustrating the electrical connections of my crossing. Fig. 6 is a view showing a modified form of crossing mechanism; and Fig. 7 is a diagram illustrating the application of my system of operation 30 to the form of crossing mechanism shown in Fig. 6.

I shall first explain generally the crossing mechanism itself, and its nature of operation, so that the operating system may be 40 fully explained and best understood. In the drawings I illustrate only a single track crossing; but it will be understood that my system may be applied to a crossing of any number of tracks as desired either by mere 45 duplication of the mechanism or by making one control device control the crossing mechanisms at the intersections of one or more tracks with one or more other tracks. In these drawings I show the rails A and B 50 of two tracks crossing each other; and the portions A' and B' of these rails between

the individual rail intersections are vertically movable in the manner described in my Patent No. 1074082, issued September 23, 1913. These vertically movable rail portions A' and B' join at the four rail intersections in the manner shown; and mechanism is employed for alternately raising and lowering the pairs of rail portions A' and B'. This mechanism may preferably be constructed as follows: Under each of one pair of these rail portions I mount a shaft 10 in bearings 10^a which carries at each end a pair of cams 11 and 12. Each of the rail portions A' has an extension or foot 13 which bears upon a cam 12 at each end of the rail portion; so that the two rail portions A' are each supported at each end upon a cam 12, of which there are four. Each one of the rail portions B' has an extension or foot 14 which bears upon a cam 11; so that the rail portions B' are each supported at each end upon a cam 11, there being four of these cams. Each one of the extensions or feet, 13 and 14, has members 15 attached thereto, with lugs 16 projecting inwardly under the overhanging edge 17 of the cam; so that the cam not only acts to raise the foot 13 or 14, but also acts to pull the foot downwardly, and therefore to 20 pull the rail portions downwardly. The cams are so designed and arranged that a revolution of about 270° will cause the rail portions to move through their full vertical movements, between the positions indicated 25 in Fig. 2. In Fig. 2 the rail portion B' is shown in its lowermost position and the rail portion A' in its uppermost position. A train of gears 20, 21 connects the two shafts 10 so as to cause their simultaneous rotations at equal speeds in opposite directions in such a manner as to cause all the cams 11 and all the cams 12 to work together to simultaneously raise and lower the rail portions. This train of gears is driven from 30 a suitable motor 25 through gearing connection 26; and the motor is controlled by the means hereinafter to be explained, being caused to rotate alternately in opposite directions so as to rotate the shafts 10 alternately in opposite directions through approximately three-fourths of a revolution 35 40 45 50 55 60 65 70 75 80 85 90 95 100

upon each movement; causing the rail portions A' and B' to be alternately raised and lowered.

Each rail portion A' or B' has at each end 5 an upwardly facing shoulder 27 which is adapted to bear upwardly against the under face of the end of the corresponding rail, A or B, when the rail portion is fully raised and when its upper tread surface is in line 10 with the upper tread surface of the rail. This is when the cam has raised the rail portion to its full height, the parts being so designed that the rail portion is then firmly held against vertical movement either up or 15 down, between the cam and the under surface of the permanent rail.

The motor 25 is controlled by a suitable system of switches, which system includes a reversing switch actuated directly from the 20 crossing mechanism itself. This reversing switch is more particularly shown in Figs. 1 and 3. On one of shafts 10 I place a double armed member 30, adapted to engage and move a slider 31. The two arms of members 30 carry rollers 32, which engage with the slider 31. The slider slides on suitable horizontal rods 33; and a switch actuating rod 34 is connected directly to the slider at 35, this connection being adjustable by 30 means of set screw 36. The rod 34 extends horizontally and connects at 37 with arm 38. Arm 38 is mounted upon a hub 39 rotatable upon a pivot 40; and this same hub carries the switch arm 41. Switch arm 41 carries 35 a contact 42 which is adapted to engage and make connection between either of a pair of contacts 43 or 44. The hub 39 also carries a gear sector 45 meshing with a pinion 46 mounted upon shaft 47; and this shaft 47 40 also carries a disk 48 having two stop shoulders 49 in the positions illustrated. A switch actuating spring 50 is held stationary at one end at 51 and connects at its other end at 52 with the disk 48 at the point indicated. 45 In the position of the mechanism illustrated in the drawings, the spring 50 is holding the disk 48 in the position shown, and is therefore holding the switch arm in the position shown with the movable contact 42 making 50 connection between the stationary contacts 43. Suppose now, that the motor 24 is rotating to rotate the shafts 10 in the directions indicated. When the shafts have rotated almost three-quarters of a revolution, 55 the roller 32 of member 30 (the one appearing to the left in Fig. 3) will move around in the direction indicated and will engage the slider 31 and then move it to the left in Fig. 3. The switch rod 34 and switch arm 41 will move to the left with the slider; and this movement will continue until the switch has moved slightly past a central position. When this has occurred, the pinion 46 and disk 48 will have rotated in the direction indicated in Fig. 3, to such a position that

the point of connection of the spring at 52 is somewhat below the horizontal plane of the shaft 47. The spring 50 will thereupon exert its force to continue the rotation of the disk 48 and pinion 46 in the direction indicated; so that these parts will then be quickly moved in the direction indicated until the stop shoulder 49 (the one which appears uppermost in Fig. 3) will have engaged the stop member 55. This will occur 75 when the disk 48 and pinion 46 have revolved about a half revolution in the direction indicated from the position shown in Fig. 3. When the parts are in the position shown in Fig. 3, the other stop shoulder 49 is in engagement with the stop member 56, as illustrated. Stop members 55 and 56 are preferably made of wood set with their grain upright. The spring impelled forward movement of the disk and pinion 46 85 will carry the switch arm on in the direction indicated to its position where the movable contact 42 engages and makes contact between the two stationary contacts 44. During this spring impelled movement the 90 rod 34 and the slider 31 have also been carried along independently of the movement of the member 30. In other words, the switch mechanism is actuated by the crossing mechanism and from the motor; but after its 95 actuation proceeds to a certain point, the movement of the movable contact 42 from the contacts 43 to the contacts 44 then takes place automatically and independently of the operation of the motor. When the motor 100 operates in a reverse direction, to rotate the shafts 10 in the directions opposite to those indicated, the member 30 engages the slider 31 to move it in the direction opposite to that just described; and the switch mechanism is actuated in the direction opposite to that just described, but in the same general manner. In the drawings the movable contact 42 is shown in engagement with stationary contacts 43; and the rail portions A' 110 are shown elevated. When current is supplied to the motor through the contacts 42 and 43, the motor rotates in such a direction as to rotate the shafts 10 in the directions indicated, to lower the rail portions A' and 115 to raise the rail portions B'. In other words, the mechanism is shown in its position where the rails A are clear for passage of a train. This is the normal position.

In Fig. 5 I show a preferred arrangement of my system for supplying current to the motor, for controlling the actuation of the crossing. In this form of device I provide that only trains passing on the track B in either direction shall operate the crossing. Insulated sections 60 are provided in the rails of track B, one on each side of the intersection with track A; these insulated sections are arranged with reference to the track A and with reference to the spacing 130

between the trucks of the car so that once the wheels of a car have entered upon the insulated section 60 on one side of the crossing, then there will be, from that instant 5 until the instant when the last wheel of the car has passed off the insulated section on the other side of the crossing, constantly one or more wheels upon one or other of the insulated sections 60. The sections 60 may be 10 of proper length to give time for actuation of the crossing mechanism between the time of first entry of the first car wheel upon one of the sections and the time when the first car wheel reaches the crossing. In 15 street railway practice I find that a length of about 20 feet is sufficient. Fig. 5 shows diagrammatically the relation of the spacing of the car wheels W to the lengths and spacings of the insulated sections 60. Each of 20 the sections is longer than the maximum distance between adjacent wheels; and the distance between the foremost and rearmost wheels is also longer than the distance between the inner ends of the insulated sections; so that, as hereinbefore stated, from 25 the time the first wheel enters upon one of the sections 60, to the time when the last wheel leaves the other section 60, there is constantly at least one wheel upon one of 30 the sections 60.

Electrical connection is made between the two sections 60 by a wire 70. One of the sections 60 is connected by wire 71 with one side of secondary 72 of an A. C. trans- 35 former 73 adapted to deliver a low voltage, say about 1.5 volts. I find that, for street railway work, the use of alternating current on the insulated rail sections is more effective than the use of direct current; al- 40 though, so far as the essentials of my invention are concerned, direct current may be used. The other side of the transformer sec- 45 ondary is connected by wire 74 to the opposite rail B. When a car wheel is in con- 50 tact with either of the sections 60, the sections 60 are connected through the wheels and axle directly with the other rail B, causing a short circuiting of the circuit of the transformer secondary. When there is no 55 car truck in position to make circuit between sections 60 and the opposite rail B, the alter- 60 nating current flows through the wire 75 to solenoid 76 of relay 77, normally raising the relay armature 76^a and causing the movable contact 78 to make connection between the relay contacts 79. The current through relay solenoid 76 passes thence through wire 80 back to rail B and thence through wire 74 and to the secondary 72. Thus, ordi- 65 narily, the contacts 79 are connected. Suppose now, that a car passes over the track B, di- 70 verting current from relay solenoid 76, as hereinbefore stated. The relay armature drops and connection is made between relay 75 contacts 81. When this occurs battery cur-

rent will flow from the storage battery 82 through wire 83, contact 81, relay contact 78, contact 81, wire 84, contact 43 of the motor actuated switch mechanism, movable contact 42 of that mechanism, the other contact 70 75 43, wire 85, a relay solenoid 86, wire 87, and wire 88, back to the battery 82. It has hereinbefore been stated that the normal position of the parts is shown in Figs. 1 to 3, with the rail portions A' elevated and with 80 the switch contact 42 engaging and making connection between stationary contacts 43. The battery current thus flowing through the solenoid 86, draws up armature 67 of the relay and moves the two movable relay contacts 68 into engagement with the two sets of stationary relay contacts 89 and 90. A wire connection 91 is made between the trolley circuit (or any other suitable source of electrical current) and one of contacts 90. 85 From the other contact 90 a wire 92 goes to the armature 93 of motor 25; and a wire 94 leads back from the armature to one of the contacts 89. From the other contact 89 a wire leads to the field winding 96 of the 90 motor; and from the field winding another wire 97 leads to the wire 88 which leads to battery 82. Battery 82 is connected through the wire 83 and through a ground wire 98 to the ground at G. The various resistances 95 in the circuit just described, leading from the trolley wire to the ground at G, are such that there is a proper voltage at the battery 82 to keep that battery charged. Current flowing through the circuit de- 100 scribed, will rotate the motor in the direction indicated and will cause the shafts 10 to rotate in the directions indicated, causing the rail portions B' to be elevated and rail portions A' to be lowered, and also causing the 105 switch mechanism to be thrown so that, at the last part of the motor operation, the movable contact 42 will be thrown into engagement with stationary contacts 44. This movement of the movable contact 42 immedi- 110 ately breaks the battery circuit which has been flowing, as described, through the contacts 42 and 43, and through relay solenoid 86, allowing the solenoid 86 to become de- 115 energized and thus breaking the main motor circuit at the contacts 89 and 90, thus stopping supply of current to the motor and stopping operation of the motor. In its position thus reached, the motor has moved the rail portions to their positions opposite 120 those shown in the drawings, with portions B' in upper position and parts A' in lowered position.

The movable contact 78 of relay 77 will stay in engagement with contacts 81 as long 125 as there is a car wheel upon either of the insulated sections 60. When the last wheel has left these insulated sections, then the solenoid 76 will be energized again and the movable contact 78 will be thrown up 130

against contacts 79. A circuit will then be established as follows: from battery 82 through wires 83 and 100, contact 79, contact 78, contact 79, wire 101, stationary contact 44 of the switch mechanism, movable contact 42 of that mechanism, stationary contact 44, wire 102, relay solenoid 103, and wires 104 and 88 back to the battery. The relay solenoid 103 by its energization raises 10 an armature 105 and raises movable contacts 106 against stationary contacts 107 and 108. A motor circuit is then established as follows: from the trolley through wires 91 and 109, contacts 106 and 107, wire 110, 15 wire 94, armature 93 (the current then passing through the armature in a direction opposite to that in which it passed before) wire 92, wire 111, contacts 108 and 106, wire 112, and wire 95, to the field winding 20 96 of the motor, and thence through wire 97 to the wire 88 and through the battery to the ground. Flow of current through this circuit causes rotation of the motor in the direction opposite to that hereinbefore 25 described and causes rotation of the shafts 10 in the direction opposite to that indicated, throwing the rail portions A' and B' back to their normal positions shown in the drawings, and throwing the switch mechanism back to its normal position shown in 30 the drawings; moving the contact 42 off the contacts at 44 at the end of said movement of the crossing mechanism and thus breaking the battery circuit at contacts 44, causing deenergization of relay solenoid 103 and thus causing breakage of the motor circuit at the contacts 107 and 108. The whole 35 crossing mechanism is then back in the position illustrated and the various switches 40 are then in the last mentioned positions; that is, switch contact 42 is in the position shown in Figs. 3 and 5, while the contact 78 is in its position engaging contacts 79, and the contacts 88 and 106 are both dropped so 45 as to break the motor circuit at all the points 89, 90, 107 and 108. This is the normal 50 position of the whole system.

In Figs. 6 and 7 I have shown the application of my crossing operating system to 55 a crossing mechanism different from that shown in Figs. 1 to 4. In the crossing mechanism shown in Fig. 6 the rail portions A' and B' are supported upon and by feet 118 and 119 bearing on cams 12^a and 11^a which 60 are mounted upon short diagonal shafts 120. These short diagonal shafts 120 are driven from a driving shaft 10^b through the medium of gears 121. Only half of this form of crossing is shown in Fig. 6, the other 65 half being a duplicate of the one illustrated. Driving connection between the two shafts 10^b may be by a chain connection 122. The cams 11^a and 12^a are arranged so as to simultaneously act in the same manner as hereinbefore described for the cams 11 and

12. The oscillation of the shaft 10^b is caused by the action of the two solenoids 125 and 126. These solenoids move a plunger 127 back and forth; and this plunger is connected by a rack and pinion connection 128 70 to a shaft 129. The shaft 129 is connected by sprocket chain 130 with shaft 10^b, the arrangement being such that shaft 129 makes about one-third of a revolution while shafts 120 make three-quarters of a revolution. 75

The reversing control switch C is of the same construction as hereinbefore described, with the contacts 43 and 44 and movable contact 42, and is adapted to be operated by the solenoid plunger. This may be done by 80 having an arm 134 projecting from the solenoid plunger and working between two collars 135 and 136 on the switch rod 34. When solenoid 125 is energized it pulls the plunger in the direction indicated by the arrow 85 and rotates shaft 129 and thereby rotates the cams 11^a and 12^a, raising the rail portions B' and lowering the rail portions A' in the same manner as hereinbefore 90 described. At the same time the switch contact 42 is moved over to engage contacts 44; and when solenoid 125 is energized, the contact 42 is moved back to engage contacts 43, the rail portions A' being raised again and the rail portions B' being lowered. 95

Fig. 7 shows diagrammatically the arrangement of the system as applied to solenoid actuation of the mechanism. The rails are provided with their insulated portions 100 60 and with the same electrical connections as hereinbefore described. When the solenoid 76 of relay 77 is deenergized the movable contact 78 connects the contacts 81. Current then flows from the battery 82, through wire 83, contacts 81 and 78, wire 84, 105 contacts 43 and 42, wire 85, solenoid 86 and wires 87 and 88 back to the battery. Solenoid 86 being energized, it draws up its armature 67 causing movable contact 68 to engage contacts 90. Current then flows through wire 91, contacts 90 and 68 and thence through wire 92^a to solenoid 126 and 110 thence through wire 97^a through the battery to the ground at G. When this solenoid has been actuated the contact 42 is thrown 115 over to contacts 44, as hereinabove described. When the solenoid 76 is again energized, in the manner hereinbefore described, the movable contact 78 moves up against contacts 79 and current then flows 120 from the battery through wires 83 and 100, contacts 79 and 78, wires 101, contacts 44 and 43, wire 102, solenoid 103 and wires 104 and 88 back to the battery. When solenoid 103 is thus energized, it raises its armature 125 105 and causes movable contact 106 to engage contacts 107 and current then flows from wire 91 through wire 109, contacts 107 and 106 thence through wire 94^b to solenoid 125 and thence through wire 94^a to solenoid 130

105 and thence through wire 97^b back through the battery to the ground.

It will be seen that a system of operation just described is, in all its essentials, similar to that first described, the last described being the application of my system to a different form of crossing mechanism, showing how the system may be applied to crossing mechanisms of different kinds.

10 From the foregoing, the nature of operation of my crossing operating system or apparatus will be understood as applied to the intersection of a single track with another single track; the operation as applied to the 15 intersection of one or more tracks with one or more other tracks being of the same nature. It will be observed that the apparatus is such as to cause the same operation of the crossing mechanism regardless of the direction of travel of the car approaching and 20 crossing the intersection on any one track; that is, in the drawings, regardless of the direction of travel of the car on the track B. The crossing mechanism normally remains 25 in position for passage of a car or train on one track (or set of tracks) over the crossing; and this track or set of tracks is the one on which the greater amount of traffic takes place. When a car approaches the 30 intersection on the least traveled track or tracks (represented by the track B in this case) the car (or the train of cars) sets the crossing mechanism for passage on that track or tracks, holds the crossing mechanism 35 set until the intersection is passed, and then allows the crossing mechanism to reset immediately and automatically for passage over the most traveled track or tracks. It may be said that the crossing automatically 40 and normally takes a certain predetermined position for passage of a car on one or more tracks; or that mechanism is employed whose function is to automatically and normally set and hold the crossing mechanism 45 in position for travel in either direction over one or more tracks, said mechanism being capable of actuation by a car to set and hold the crossing mechanism in its other position while that car is passing the intersection on 50 the other track or tracks in either direction.

It will be understood that I use the terms car, cars, or trains to include any object traveling on the intersecting tracks, and for 55 passage of which over the intersection the crossing mechanism must be set to afford a smooth and unbroken track.

The crossing mechanisms herein described are not the particular subject matter of this 60 application; and, so far as the invention herein claimed is concerned, these mechanisms are described only to typify crossing mechanisms which may be operated by my system. The particular forms of mechanisms herein shown are the subject matter 65 of, and claimed in, my application S. N.

156,024, filed March 20, 1917, for railroad intersection; and the following claims in this present application are directed to the operating system.

Having described a preferred form of my 70 invention, I claim:

1. In combination with two intersecting tracks and an intersection mechanism adapted to be set to make either track passable and the other simultaneously impassable for 75 cars across the intersection, means adapted to normally automatically set said mechanism for passage across the intersection on one intersecting track, and means co-operating with said last mentioned means, and controlled by a car approaching said intersection on the other intersecting track, to set and hold said mechanism for passage across the intersection on the other intersecting track, said last mentioned means including 80 an actuating circuit in which current normally flows and from which current is diverted by an approaching car.

2. In combination with a track intersection mechanism adapted to be set for passage of cars on either of two intersecting tracks over a track intersection, means adapted to normally automatically set said mechanism for passage across the intersection on one intersecting track, and means co- 90 operating with said last mentioned means, and controlled by a car approaching the intersection on the other intersecting track, to set and hold said mechanism for passage across the intersection on the other intersecting track, said means including a relay 95 controlling two circuits and a circuit normally supplying current to said relay to cause it to normally establish one of said controlled circuits, and means controlled by 100 a car approaching on the last mentioned intersecting track to divert current from said relay circuit and cause the relay to act to establish the other one of said controlled 105 circuits.

3. In combination with two intersecting tracks and an intersection mechanism adapted to be set to make either track passable and the other simultaneously impassable for cars across the intersection, means including a 115 normally closed actuating circuit for normally automatically setting said mechanism in position for passage over the intersection on one of the intersecting tracks, and means controlled by a car approaching on the other intersecting track to divert current from 120 said normally closed circuit.

4. In combination with two intersecting tracks and an intersection mechanism adapted to be set to make either track passable and 125 the other simultaneously impassable for cars across the intersection, means including a normally closed actuating circuit for normally automatically setting said mechanism in position for passage over the intersection 130

on one of the intersecting tracks in either direction, and means controlled by a car approaching in either direction on the other intersecting track to divert current from 5 said normally closed circuit.

5. In combination with a track intersection mechanism adapted to be set for passage of cars on either one or the other of two intersecting tracks over a track intersection, 10 electrically controlled means to normally automatically set said mechanism for passage across the intersection on one intersecting track, and electrically controlled means cooperating with said last mentioned means, 15 and controlled by a car approaching the intersection on the other intersecting track, to set and hold said mechanism for passage across the intersection on the other intersecting track, said means including a relay controlling two circuits connected into the first 20 mentioned electrically controlled means, a circuit normally supplying current to said relay to cause it normally to establish one of said controlled circuits, and means controlled by a car approaching on the last 25 mentioned track to cause cessation of current in said relay circuit and cause the relay to act to establish the other one of said controlled circuits.

30 6. In combination with a track intersection mechanism adapted to be set for passage of cars on either one or the other of two intersecting tracks over a track intersection, a motor mechanism adapted by 35 intermittent action to set said intersection mechanism in either of its positions, a switch mechanism adapted to control the intermittent action of the motor mechanism, embodying two pairs of switch contacts and 40 a movable contact arm actuated from the motor mechanism, two circuits connected into said motor controlling switch to its two pairs of contacts, a relay controlling said two circuits and normally standing in 45 position to establish the circuit which causes the motor mechanism to normally set the intersection mechanism for passage over one of said tracks, a relay circuit normally supplying current to the relay to hold 50 it in its normal position, and means controlled by a car approaching on the other of said intersecting tracks to cause cessation of current in said relay circuit.

55 7. In combination with a track intersection mechanism adapted to be set for passage of cars on either one or the other of

two intersecting tracks over a track intersection, a motor mechanism adapted by intermittent action to set said intersection mechanism in either of its positions, a 60 switch mechanism adapted to control the intermittent action of the motor mechanism, embodying two pairs of switch contacts and a movable contact arm actuated from the motor mechanism, two motor operating circuits connecting into the motor to cause its 65 operation, one to set the intersection mechanism in one position and the other to set the intersection mechanism in its other position, two relays severally controlling said motor 70 circuits, energizing circuits for said relays connected to the two pairs of contacts of the motor control switch, a relay controlling said two relay energizing circuits, and means, under control of a car approaching 75 on one of said tracks, to energize said last mentioned relay.

8. In combination with a track intersection mechanism adapted to be set for passage of cars on either one or the other of two intersecting tracks over a track intersection, a motor mechanism adapted by 80 intermittent action to set said intersection mechanism in either of its positions, a switch mechanism adapted to control the intermittent 85 action of the motor mechanism embodying two pairs of switch contacts and a movable contact arm actuated from the motor mechanism, two motor operating circuits connecting into the motor to cause its operation, one to set the intersection mechanism 90 in one position and the other to set the intersection mechanism in its other position, two relays severally controlling said motor circuits and adapted when energized to normally close that circuit which causes energization of the relay controlling the motor circuit that causes setting of the crossing mechanism for normal passage over one track, a circuit normally energizing said last 95 mentioned relay, and means controlled by a car approaching the intersection on the other of said intersecting tracks to cause cessation of current in said last mentioned circuit. 100

105 In witness that I claim the foregoing I have hereunto subscribed my name this fourth day of August, 1916.

EDWARD S. COBB.
